UNITED STATES PATENT OFFICE.

ANTHONY HOZLAK, OF NANTICOKE, PENNSYLVANIA.

SUBMARINE VESSEL.

Application filed March 11, 1926. Serial No. 93,934.

This invention relates to submarine vessels, and has for its object to provide a vessel of such class, in a manner as hereinafter set forth, with means to facilitate passage from 5 and to the vessel, when the latter is submerged, to enable the operation of the steering mechanism from upper and lower decks, to provide for the adjusting of the planes from upper and lower decks, and with means 10 for expeditiously pumping off the water taken up during passage from and to the vessel when the latter is submerged.

Further objects of the invention are to provide, in a manner as hereinafter set forth, 15 a submarine vessel which is comparatively simple in its construction and arrangement, strong, durable, having the several mechanisms thereof conveniently operated, and comparatively inexpensive to set up.

20 With the foregoing and other objects in view the invention consists of the novel construction, combination and arrangement of parts, as hereinafter more specifically described and illustrated in the accompanying drawings, wherein is shown an embodiment of the invention, but it is to be understood that changes, variations and modifications can be resorted to which fall within the scope 25 of the claims hereunto appended.

30 In the drawings wherein like reference characters denote corresponding parts throughout the several views:—

Figure 1 is a side elevation, broken away and partly in section, of a submarine vessel in accordance with this invention.

35 Figure 2 is a top plan view thereof.

Figure 3 is a section on line 3—3 of Figure 1.

40 Figure 4 is a fragmentary view upon an enlarged scale and in longitudinal section illustrating one of the rooms from which passage can be had from the vessel when the latter is submerged.

Figure 5 is a section on line 5—5 Figure 4.

45 Referring to the drawings in detail, 1 denotes a hull, 2 an upper deck and 3 a superstructure providing what may be termed a conning tower 4 and a cabin 5, and the latter, as well as the former, or both can be 50 employed for operating from within thereof any suitable means for training and firing the guns 6 which are mounted upon the upper deck 2. The cabin 5 has said means therein indicated at 6', but as such means 55 forms no part of this invention, it is only inferentially referred to in connection with

the employment of the conning tower and cabin to house the same. The operating means for firing and training the guns is arranged in the tower or cabin, or both, in 60 close proximity to the windows thereof to enable the operator to have a clear view when firing or training a gun. The superstructure 3 extends lengthwise with respect to the deck 2, but preferably is arranged at 65 one side thereof thereby providing a clearance to enable mounting of the guns 6 on the other side of the deck 2.

Arranged within the hull 1 is an intermediate deck 7 and a lower deck 8. Communication is established between the decks 7 and 8 as at 9. Communication is established between the decks 2 and 7 by stairways or ladders 10 and 20. The deck 2 within the conning tower 4 and also within the cabin 5 75 is formed with an opening. One of the openings are indicated at 11 and the other at 22, and the former is arranged within the conning tower 4 and the latter within the cabin 5. The openings 11 and 22 provide means 80 whereby access can be had to the stairways or ladders 10 and 20 respectively. Trap doors 23 and 23' are provided for closing the openings 11 and 22 respectively.

Positioned forwardly upon the deck 7 is 85 the operating mechanism 12 for adjusting a pair of planes 13 which extends laterally in opposite directions with respect to the sides of the hull 1. Associated with each of the planes 13 is a pair of protecting elements 90 13' and also associated with the planes 13 is a flexible element, such as a chain 13'' to limit the upward and downward movement of the plane.

The sides of the hull of the vessel and 95 which are indicated at 14, 14' in Figure 3, are provided intermediate their ends with a door opening 15, normally closed by an outwardly opening door 16. Each side of the hull 1 is formed with an inwardly extending 100 tapered flange 17 which is disposed entirely around the door opening 15, and as the door 16 is formed with bevelled edges, when the door is closed, it snugly fits the flange 17 to prevent leakage. Each door 16 is hinged to 105 the outer face of a side of the hull, as at 16. and provides an outlet for a chamber or room 19 having its bottom formed by a portion of the deck 7. Each chamber or room 19 is positioned adjacent the longitudinal 110 median of the hull 1.

One side wall of one of the chambers or

rooms 19 is provided by the side 14 of the hull and one of the side walls of the other chamber 19 is formed by the other side 14' of the hull. The side walls for said chambers which are provided by the sides of the hull are the outer side walls thereof. Secured to the upper deck 2 and to the intermediate deck 7 is a pair of longitudinally disposed vertically extending spaced partitions 24, 24' and each of which is provided with a transparent panel 24" mounted in an opening 24'" formed in the partition and which provides a window to enable one to view the interior of a room or chamber 19.

Secured to the deck 2 and to the intermediate deck 7, and also to a partition 24 or 24' and further to a side of the hull is a pair of vertically extending partition members 25, 25' which form the end walls of a chamber or room 19. Secured to the sides of the hull below the deck 7, as well as spaced therefrom, is a flanged plate 26 which provides the bottom of a water collecting tank. The top of the tank is formed by the deck 7. The sides of the tank are indicated at 26', 26'' and which are formed by a pair of plates secured to the deck 7 and to the plate 26. The partitions 25, 25' are secured to the deck 7 at the lower ends thereof and although it has been stated that the deck 7, plates 26' and 26'' provide a water collecting tank, yet it is thought that the said plates in connection with the deck 7 provide what may be termed a water collecting chamber and which is indicated at 28. The floor of each of the chambers or rooms 19 is provided with an opening 29 for establishing communication between the chambers 19 and the water collecting chamber 28. The openings 29 are normally closed by trap doors 30 which open inwardly into the chambers or rooms 19. The doors 30 are hinged as at 31 to the floors of the chambers or rooms 19. Depending from the deck 7 and surrounding each opening 29 is a tapered flange 30' and as the doors 30 are of tapered construction a snug fit or water tight fit is had when the doors 30 are engaged with the flanges 30'.

Arranged on the deck 8, below the chamber 28, as well as communicating therewith, as at 32, are two pumps 33, having a discharge line 34 extended through the side 14 of the hull. Each pump 33 is operated by means of an electric motor 35 which is mounted on the deck 8. Each pump 33 is employed for drawing off water from the chamber 28. Each line 34 is provided with a controlling valve 34', operated from the deck 7 by a stem 34".

Secured to each side of the hull and projecting laterally therefrom, at the door opening 17, is a platform 36. The partition 24 or 24' is formed with a door opening 37, closed by a door 38, which is hinged to such partition, as at 39, and said door 38 opens into the chamber 19 and permits of access being had to the chamber 19 from the deck 7. The door 30 has secured to its upper face an inverted T-shaped member 40 and pivoted thereto is a pair of links 41 which are also 70 pivoted to an arm 42 of a bell crank lever 43 which is pivotally connected as at 44 to a support 45. The other arm of the lever 43 is indicated at 46. A bell crank lever 43 is provided for opening the door 30 whereby 75 communication is established between the room 19 and the chamber 28 and further acts as a means for closing the door 30 to shut off such communication. Each door 16 is swung to open and closed position through 80 the medium of a shifting mechanism therefor and which consists of a rack bar 47, having pivotally connected to one end thereof as at 48, a link 49, which is pivotally connected as at 50, to a T-shaped member 51, secured to the inner face of the door 16. Secured to one end wall of each room 19 and also to the inner face of a side of the hull, is a bracket 52, which includes an inverted L-shaped arm 53 in which is journaled a gear wheel 54 meshing with the rack 47 and operated through the medium of a crank 55. When the crank 55 is operated to revolve the gear 54 in a clockwise direction the door 16 is shifted to the position illustrated in dotted lines in Figure 5 and when the gear 54 is revolved in an anti-clockwise direction the door 16 is moved to closure position with respect to the opening 15.

Each room 19 is employed to permit of 100 passage from and to the vessel when the latter is submerged. A diver being in a room 19, is allowed to pass therefrom by opening the door 16 where he passes upon the platform 36. The door 16 is then closed by another diver or some other person in the room 19 and the door 30 opens so that the water from the room 19 will pass into the chamber 28 and from where it is exhausted and drawn off by the pump 33. After the room 19 has 110 been cleared of water, the door 30 is closed.

The rudder of the vessel is indicated at 56, and is carried by a vertically extending rudder shaft 57 supported in brackets 58, 59. The upper end of the rudder shaft 57 is formed with a bevelled gear 5 which meshes with a bevelled gear 60 formed on the rear end of a rudder operating shaft 61 in sections which are geared together at 61'. The shaft 61 is of a length to extend from the stern of the hull to a point below the conning tower 4. Bearings 62, 63 are provided for the shaft 61 and the forward end of the latter is provided with a bevelled gear 64, and in proximity to said gear 64 with a bevelled gear 65. The bevelled gear 64 meshes with the bevelled gear 66, on the lower end of an actuating shaft 67, carrying on its upper end a bevelled gear 68, which is 125 engaged and operated by a bevelled gear 69,

carried by a shaft 70 provided with a hand wheel 71. The hand wheel 71 is arranged within the conning tower 4 and provides means whereby the steering mechanism can be operated from the upper deck 2. Supported by a pair of superposed brackets 72, 73, is a vertically disposed shaft 74, having its lower end provided with a bevelled gear 75. Carried on the upper end of the shaft 74 is a bevelled gear 76, which meshes with a bevelled gear 65, carried by the shaft 61. Meshing with the bevelled gear 75 is a bevelled gear 77, carried by a shaft 78 journaled in the upper end of a standard 79, and provided with a hand wheel 80. The standard 79 is secured to the deck 7. The shaft 78, in connection with the bevelled gear 77, hand wheel 80, shaft 74 and its several gears provides means for operating the steering mechanism from the intermediate or a lower deck.

The adjusting mechanism 12 for the planes 13, can be operated from the conning tower 4, or from the deck 7, and for such purpose a pinion 81 is provided, carried by a shaft 82, and which meshes with a rack 82' of the mechanism 12. The shaft 82 is suitably supported and the pinion 81 meshes with a gear 84 carried by a shaft 85 provided with a hand wheel 86. The shaft 85 is mounted in standards 86' secured to the deck 7. Extending down through the floor of the conning tower 4 is a vertically disposed shaft 87 provided at its lower end with a bevelled gear 88 which meshes with the gear 84. The upper end of the shaft 87 is provided with a gear 89 which meshes with a gear 90 carried by a shaft 91 provided with a hand wheel 92. The shaft 91 is mounted in a standard 93 secured to the floor of the conning tower 4. By this arrangement when the hand wheel 92 is operated within the conning tower 4 the planes can be adjusted, as the operating mechanism 12 will be actuated. If the hand wheel 86 on the deck 7 is operated then the mechanism 12 will also be actuated to adjust the planes. The propellers of the vessel are indicated at 93', the shafts therefor at 94 and which extend from the sides of the hull and are journaled in lateral brackets 95. Each shaft 94 has a pair of three blade propellers 93'.

The side wall 26' of the water chamber or tank 28 is provided with an opening normally closed by a swinging door 95, and which when open will permit of passage of water from the interior of the hull to the chamber 28 so that such water can be pumped out by the pump 33.

Extending into each chamber or room 19 is an air pipe 96 provided with a valve 97 at each end. The pipe 96 is mounted near the top of the partition 24 or 24' and has its inner end arranged within the hull 1.

The valved pipe 96 is provided for controlling a supply of air to a chamber or room 19.

Extending from the conning tower 4 and cabin 5 to the collecting chamber or tank 28 are valved water pipes 98, 99 respectively. The tower 4 and cabin 5 are closed water tight and the top wall of each is provided with an outwardly opening door 100 seated in a door opening 101. Arranged within 75 and at the side of tower 4 and cabin 5 are respectively step ladders 103 and 104.

Arranged exteriorly of each side of the hull, as well as being secured therewith is a stairway or ladder 102 which extends 80 from the platform 36 to the deck 2. Railings 105, 106 extend respectively around deck 1 and the top of the superstructure.

The several doors hereinbefore set forth, are of the water tight type. The construction hereinbefore referred to, with respect to the operating mechanism 12 for the planes, provides what may be termed a dual means for operating such mechanism, and this latter statement also applies to the steering mechanism, for the reason that a dual actuating means is set up therefor. The construction heretofore described, also provides means to permit of convenient passage from and to the vessel, and further means whereby the water which enters the vessel, during the passage from and to the vessel, will be expeditiously drawn off. Therefore it is thought the many advantages of a submarine in accordance with this invention can be readily understood, and although the preferred embodiments of the invention are as illustrated and described, yet it is to be understood that changes in the details of construction can be had which will fall within the scope of the claims hereunto appended.

What I claim is:—

1. A submarine comprising a hull provided with an upper and a lower deck, a super-structure on said upper deck, a rudder operating shaft extending lengthwise of said hull and arranged in proximity to and below said upper deck, means mounted in said super-structure and extending through said upper deck and operatively engaging the forward end of said shaft for actuating it, and means mounted on said lower deck and extending upwardly towards and operatively connected with said shaft for operating it whereby said steering mechanism can be operated from said super-structure or from said lower deck.

2. A submarine comprising a hull provided with an upper and a lower deck, a super-structure on said upper deck, a pair of laterally disposed planes arranged on each side of said hull at the forward portion thereof, shifting mechanism for said planes extending lengthwise of said lower deck forwardly

thereof, means arranged on said lower deck and operatively engaging with said shifting mechanism for actuating it, and means mounted in said super-structure and extending through said upper deck and operatively engaging with said actuating means to provide for the operation of said shifting mechanism from said super-structure.

3. A submarine comprising a hull provided with an upper and a lower deck, a super-structure on said upper deck, an operating mechanism common to a pair of planes and extending lengthwise of the lower deck, actuating mechanism for said operating mechanism extending from said super-structure, through said upper deck and to said lower deck, means arranged within the super-structure for operating said actuating mechanism to provide for the operation of the plane operating mechanism, and means arranged on the lower deck for operating said actuating mechanism to provide for the operating of the plane operating mechanism.
4. A submarine comprising a hull provided with an upper and a lower deck, a super-structure on said upper deck, a rudder operating shaft extending lengthwise of said

hull and below said upper deck, means mounted in said super-structure and extending through said upper deck and operatively engaging with said shaft for actuating it, and means mounted on said lower deck and extended upwardly therefrom and operatively connected with said shaft for operating it whereby the steering mechanism can be operated from said super-structure or from said lower deck.

5. A submarine comprising a hull provided with an upper and a lower deck, a super-structure on said upper deck, a plane operating mechanism extending lengthwise of said lower deck forwardly thereof, actuating mechanism for said plane operating mechanism extending from said super-structure, through said upper deck and to said lower deck and operatively connected with said operating mechanism, and means arranged within the super-structure and on the lower deck and permanently engaging with said actuating mechanism whereby said plane operating mechanism can be operated from said super-structure or from said lower deck.

In testimony whereof, I affix my signature hereto.

ANTHONY HOZLAK.
